CAN BODY

Basil F. Saubestre, Elmhurst, N. Y., assignor to
American Can Company, New York, N. Y., a
corporation of New Jersey

Application November 19, 1945, Serial No. 629,643

4 Claims. (Cl. 220—76)

1

The present invention relates to containers or cans and has particular reference to improvements in reenforcing the side seam of a can body and more specifically to improvements on the can bodies disclosed in United States Patent 2,259,498, issued October 21, 1941, to R. C. Taylor, on Can body, and in United States Patent 2,064,537, issued December 15, 1936, to W. E. Groenke, on Can body.

The present invention contemplates the provision of a can body having a side seam capable of withstanding the high internal pressures developed in some liquids such as beer when enclosed and hermetically sealed in cans made from such bodies and pasteurized or otherwise treated, the side seam being disposed in such a manner as to present a smooth interior surface in the can to facilitate interior coating of the can.

In cans having side seams located wholly within the can, it has been found difficult to satisfactorily cover the rounded edges of the seam with a liquid coating substance during the can lining operation. The coating substance has a tendency to drain away from the edges of the seam and thus leave them partially coated or entirely uncoated and hence expose or partially expose the material of the can to the deleterious effects of the contents.

Where the side seam is reenforced by a reshaping of the seam on the interior of the can to withstand the high internal pressures of beer and the like, a great many more rounded edges are formed which aggravate the matter considerably.

In order to obtain ideal conditions for internal coating of the can, it is preferable to locate the seam entirely on the exterior of the can. However, in a lap and lock seam this ideal location presents numerous soldering difficulties when operating under high speed rates of production. The production of such a seam is further complicated by the proper venting and maintenance of sufficient capillary action through the seam to insure a proper flow of solder to all parts of the seam to produce a strong fully soldered seam joint.

The instant invention contemplates overcoming these difficulties by producing cans with an improved reenforced seam which is located partially within the can and is reenforced exteriorly of the can in such a manner as to present a smooth interior surface which facilitates internal coating of the can while maintaining a fully soldered strong seam free of islands or other unsoldered portions within the seam.

An object of the invention is the provision of a can body capable of withstanding high internal pressures, having an improved reenforced side

seam made up of a plurality of sections or zones of different thicknesses of material and having alternate hooks and overlaps, interlocked and imbedded from the exterior of the seam in such a manner as to present a substantially smooth surface interiorly of the can body to facilitate coating of the body, these hooks and overlaps being separated by reentrant notches formed along the side seam edges of the body to permit the escape of air or gases when the side seam is soldered to provide a fully bonded side seam of maximum strength and pressure resistance.

Another object of the invention is the provision of a soldered side seam made up of alternate interlocked and overlapped sections along one of the parts of the side seam and these sections have close bonding connection with a longitudinally extending hook formed as another part of the seam wherein the overlapped sections are vented by vent notches and the material of the body at the overlap is interlocked with the overlap sections to provide capillary action for the solder applied to the outside of the seam to insure a fully bonded seam free of islands or other unsoldered portions.

Numerous other objects and advantages of the invention will be apparent as it is better understood from the following description, which, taken in connection with the accompanying drawings, discloses a preferred embodiment thereof.

Referring to the drawings:

Fig. 1 is a perspective view of a can body embodying the present invention, the body being shown after the side seam has been completed, with the parts closed and hermetically sealed together;

Fig. 2 is a perspective view of a tubular shaped partially formed can body showing one stage in the formation of the side seam;

Fig. 3 is a face view of a body blank properly cut to provide for the can body shown in Figs. 1 and 2;

Fig. 4 is a view similar to Fig. 2 showing a further step in the formation of the side seam;

Figs. 5, 6 and 7 are enlarged transverse sectional details taken at different positions along the side seam substantially as indicated by the respective lines 8—8, 6—6, 1—1 in Fig. 1;

Fig. 8 is an enlarged fragmentary longitudinal section of a portion of the side seam as viewed along the broken line 8—8 in Fig. 1, with parts broken away; and

Fig. 9 is a view similar to Fig. 6 and showing a modified form of the invention.

As a preferred embodiment of the instant in-

vention the drawings illustrate a sheet metal can body made of tin plate or the like material and produced from a formed and notched flat blank 10 (Fig. 3). One of the side seam edges of the body blank is notched to form end notches 11, there being illustrated two such notches, one adjacent each end of the blank. This provides an end lap region 12 at each corner of the blank and a longitudinal central part 13 extending along the edge and in between the end notches. This longitudinal central part 13 is formed with a plurality of shallow reentrant vent notches 14 spaced at intervals along the blank edge. The drawings show three of these notches although any number may be used as desired.

On the opposite side seam edge of the blank similar end notches 15 are cut, one adjacent each corner of the blank. At each of these positions the corner is clipped off along an angular line 16 leaving an angular end lap region 17 at each end of the blank. A series of pairs of relatively deep reentrant vent notches 18 are also cut in the blank in spaced relation along this edge and these notches are in transverse alignment with the notches 14 in the opposite edge of the blank.

Each pair of notches 18 defines a lug 19 therebetween. This notching of the blank edge produces end edge or outer sections 21 which are set off between each end notch 15 and a single notch 18 of each pair adjacent. It also isolates two central edge or inner sections 22 which are set off between spaced reentrant notches 18 intermediate adjacent lugs 19.

The blank is rolled or otherwise bent into cylindrical shape, as illustrated in Fig. 2, and the longitudinal blank edge 13 is bent back to provide a single continuous hook 25 containing the vent notches 14. These notches 14 extend back into the hook just a short distance (about one thirty-second of an inch in an ordinary size of can body). In a similar manner the blank edges 21 on the opposite side of the blank are bent in to provide a pair of hooked-in sections 26 and the intermediate edge sections 22 are bent in the same manner to provide a pair of turned-in hook sections 27. This bending of the edge sections 21, 22 into the hook sections 26, 27 sets off under the lugs 19, a plurality of recesses 28 which include the reentrant notches 18. This produces the structure illustrated in Fig. 2.

The open edges of the formed blank are then united, the longitudinal or single continuous hook 25 being engaged with the turned-in hook sections 26 and the turned-in hook sections 27 as illustrated in Fig. 4. The angular or cut-away lap portions 17 come just outside of the end lap sections 12 and the lugs 19 project over the outside wall of the can body adjacent the vent notches 14 in the hook 25, with these notches 14 in registry with the recesses 28 under the lugs.

A bumped side seam is then formed by pressing together the interlocked parts, this action bringing the angular end lap sections 17 into metal to metal contact with the end lap sections 12. The lugs 19 are pressed into close metal to metal engagement with the body wall adjacent the hook 25 and are forced inwardly from the exterior of the body into the outer surface of the body.

In this bumping or pressing of the seam, portions of the two outer layers of the seam adjacent the lugs 19, i. e., the wall of the body and its connecting hook 25, are pressed inwardly from the exterior of the body into the recesses 28 as best shown in Figs. 6 and 8 to fill in the spaces

5 of the recesses and to reduce the thickness of the seam at each lug to reinforce the seam. This forms a plurality of depressions 29 in the seam on the outside of the body while leaving the seam on the inside straight and smooth.

6 Along one side of each of the depressions 29 the metal of the outer layer of the seam is bent down into the vent notches 14, as shown in Figs. 6 and 8, to form projections 33 to fill in these 10 notches.

7 During this bumping or pressing and indenting of the seam part each lug 19 is pressed down into the underlying wall of the body, thus forming a pocket or hollow 35 for the lug (Figs. 6 and 8).

15 At the same time the wall of the body, adjacent the side seam is bent outwardly into alignment with the outer layer of the seam as best shown in Fig. 7. This bending of the body wall forms two tapered wall sections 36, 37 which slope away 20 from the side seam and merge into the peripheral line of the body wall in a smooth contour which facilitates lining or coating of the body interior surface.

25 This bending of the body wall also forms a shallow trough 38 (Fig. 7) adjacent the rounded inside edge of the seam which collects sufficient coating substance during the lining operation to prevent the coating substance from draining away from the seam edge to expose the edge.

30 The bending of the edges of the blank, the interlocking of the hook parts and the pressing together of the seam sections as just described are all done automatically during the manufacture of the can by the usual body maker or other type of body forming machine. The side seam is then hermetically sealed by the introduction of solder applied from the outside in the usual manner. The distribution of the solder in the finally prepared seam is graphically illustrated in Figs. 5, 6, 7 and 8, the solder being designated by the numeral 42.

35 As will be observed by referring to Fig. 5 the outer lap section 17 is indented or slightly raised to receive the inner lap portion 12. The parts 12, 45 17 are first bumped into close metal to metal contact and then the solder 42 flows into and tightly bonds these parts together.

40 Figure 6 more clearly illustrates how the lugs 19 are pressed into the body wall to provide the pocket 35 which is filled with solder. At this point the section of the longitudinal hook 25, which is directly in line with the notches 14, is pressed tightly against the other part of the hook or flattened as indicated at 43.

45 This hook zone for a width equal to the notches 14 is not interlocked with the other parts of the seam. The projections 33 adjacent the base of the lugs 19 extend down into the notches 14 formed in this pressed down hook section 25 and terminate adjacent the edge of the hook. This fills the space so that a narrow channel is formed through the seam at this position to insure capillary action of the solder. The solder 42 at this position not only fills in the

50 pocket 35 but also flows between and binds together the flattened sections of the hook 25 and also binds it with hook projections 33 and the body wall at the depressions 29. The resulting interior wall of the body is in this manner made 55 smooth and straight, as hereinbefore mentioned.

58 In Fig. 7 there is illustrated the full hooked position of the hook 25 where it interengages with one of its hooks 27, this interlocked condition being designated by the numeral 44. Here 75 again solder closely binds the parts together.

In Figs. 5 to 8, inclusive, which are drawn to an enlarged scale it has been necessary to greatly exaggerate the thickness of the body wall and also the thickness of the solder. This should be kept in mind when viewing these figures. In reality there is metal to metal contact in the lapped and hooked sections and the film of solder therebetween is indeed very thin.

In the modified form of the invention as illustrated in Fig. 9 the vent notches 14, the depressions 29, and the seam hook projections 33 are applied to a can body of the type shown in the above mentioned Groenke patent, in which the lugs 19 are omitted as is sometimes desirable for certain kinds of cans. In such a construction of can body the hook projections 33 terminate at the folded edge of the hook 25 and no not merge into an overlapping lug as in the preferred form of the invention. The omission of the lugs 19 however does not in any way alter the invention.

This construction and the use of different types of sections of interlocked and overlapped edges together with the hook projections 33 and the complete venting afforded by the reentrant notches 18 and the vent notches 14, reinforce the side seam and prevents any pulling away or unrolling of the intermediate seam parts. The forming of the depressions 29 in the outer surface of the seam and the forming of the tapered wall sections 36, 37 and the trough 38 on the inside of the body provide a substantially smooth interior for the body so that lining of the interior surface is facilitated, as hereinbefore mentioned.

The resulting can body is much stronger than a can body not so reenforced and experiment has shown that such a can body may be embodied in a can suitable for packaging beer where great internal pressures are often developed. The smooth interior of the can body also insures that all surfaces including those of the side seam are thoroughly covered with the lining substance so that no exposed surfaces obtain.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A reenforced can body capable of resisting high internal pressures and having inner and outer marginal hook edges bent in opposite directions along predetermined lines of fold interlocked in a side seam and secured together in a solder bond in the side seam, a plurality of open vent notches extending inwardly from the outer edge of the inner hook at spaced intervals therealong, and a straight non-folded portion of the can body on the outside of said body adjacent each of said notches extending into and substantially filling said notches to provide vented passageways through said seam for the capillary action of solder applied to the outside of the seam to insure a fully bonded seam free of islands and other unsoldered portions.

5 2. A reenforced can body capable of resisting high internal pressures and having inner and outer marginal hook edges bent in opposite directions along predetermined lines of fold interlocked in a side seam and secured together in a solder bond in the side seam, a plurality of vent notches formed in both of said hooks at spaced intervals therealong, the notches in one of said hooks being in alignment with the notches in the other of said hooks, a portion of said inner hook adjacent the notches therein extending into the notches in said outer hook, and a portion of the can body on the outside of said body adjacent each of said notches in said inner hook extending into and substantially filling said notches in said inner hook to provide vented passageways through said seam for the capillary action of solder applied to the outside of the seam to insure a fully bonded seam free of islands and other unsoldered portions.

10 3. A reenforced can body capable of resisting high internal pressures and having inner and outer marginal hook edges bent in opposite directions along predetermined lines of fold interlocked in a side seam and secured together in a solder bond in the side seam, a plurality of shallow vent notches formed in one of said hooks at spaced intervals therealong, a plurality of deep vent notches formed in the other of said hooks in alignment with said shallow vent notches, a portion of said hook having the shallow vent notches extending into and substantially filling said deep vent notches, and a portion of the can body extending into and substantially filling said shallow vent notches to provide vented passageways through said seam for the capillary action of solder applied to the outside of the seam to insure a fully bonded seam free of islands and other unsoldered portions.

15 4. A reenforced can body capable of resisting high internal pressures and having inner and outer marginal hook edges interlocked in a side seam and secured together in a solder bond, a plurality of seam venting notches formed in said inner hook at spaced intervals therealong, a plurality of alternate relatively narrow overlapping portions separated by open substantially V-shaped reentrant notches formed in said outer hook, said overlapping portions engaging the outer surface of the body adjacent the seam and impressed into the outer surface of the can body, portions of said can body adjacent its overlapping portions extending into and substantially filling said venting notches in said inner hook to provide capillary acting passageways in said seam to facilitate the penetration of solder applied to the outside of the seam to insure a fully bonded seam.

BASIL F. SAUBESTRE.
